PLIABLE METAL CLOSURE

John W. Thomas, New Kensington, Pa., assignor
to Aluminum Company of America, Pittsburgh,
Pa., a corporation of Pennsylvania

Application March 18, 1941, Serial No. 383,935

6 Claims. (Cl. 215—43)

This invention pertains to container closures, particularly to closures drawn from pliable metal such as aluminum. The invention also relates to combinations of pliable metal closures with containers such as milk bottles.

Many cup-like, pliable metal closures have been previously manufactured. Among these have been closures having straight-tapered skirts and closures having stepped-tapered skirts. Likewise, closures have been produced having skirt portions to some extent pleated, folded, fluted, knurled, or otherwise shaped. The straight or stepped skirt closures have been produced to accommodate the closures to particular container finishes. The shaped or knurled skirt closures have been produced in efforts to take up excess metal resulting from the closure drawing operation, to provide gripping surfaces, or to provide decorative appearances. These prior practices and the closures on which they were employed are disclaimed from the present invention insofar as they have been separably employed.

Containers are now being employed which require the use of deep skirted closures. In particular, containers are employed which require a closure having a skirt of both stepped and reinforced construction. The present invention combines these desirable features of construction in a closure having upper and lower frusto-conical skirt portions joined by a knurled midportion, the closure preferably being stepped at the knurled portion as will be described.

It is an object of this invention to provide a cup-like, pliable metal closure with a reinforced skirt, particularly with a skirt having a reinforced mid-section.

Another object of the invention is to provide a drawn, cup-like, pliable metal closure with a skirt formed of parallel frusto-conical portions. Particularly, it is an object to provide a stepped closure skirt formed of parallel frusto-conical portions with a reinforced midportion joining the same.

Another object of the invention is to provide a deep-skirted closure suitable for a container which has a relatively wide relieved portion or groove in the outside finish thereof. It is a particular object to provide a closure for such a container which is adapted to be reformed on upper and lower engaging surfaces of the container and which is self-supporting opposite a relatively wide groove therebetween.

A further object is to provide a novel combination of closure and container wherein a closure having a reinforced skirt is applied to a container

having a relatively wide relieved portion or groove midway between closure engaging surfaces thereon.

Further objects and advantages of the invention will be observed upon reading the following description with reference to the drawing.

Fig. 1 is a plan view of a container closure conforming to the invention;

Fig. 2 is an elevation, partly in section, of the closure shown in Fig. 1;

Fig. 3 is an elevation, partly in section, of the orifice of a container to which a closure may be applied;

Fig. 4 is an elevation, partly in section, of the orifice of a container to which a closure has been loosely applied; and

Fig. 5 is an elevation, partly in section, of the orifice of a container on which a closure has been reformed.

The closure of the present invention is preferably a drawn, cup-like metal closure made from aluminum of about 0.003 inch in thickness. This material is relatively thin, pliable, and easily deformed. It has strength characteristics adequate for the mechanical reformation of a closure formed therefrom onto suitable closure retaining means on containers. The closure is preferably formed by drawing so as to have an upper frusto-conical skirt portion joined by a knurled mid-section to a lower frusto-conical skirt portion. In the preferred form of the closure, the roots of the knurled mid-section lie in approximately the same surface of revolution as the upper frusto-conical portion, and the crests of the knurled mid-section lie in approximately the same surface of revolution as the lower frusto-conical portion. By forming the closure in this manner, upper and lower closure retaining impressions may be made in the skirt of the closure at the upper and lower frusto-conical portions, without distortion of the mid-section. The mid-section will have been strengthened and adapted to retain its shape by reason of the knurling imparted thereto.

This closure is particularly adapted to the sealing of containers provided with upper and lower engaging surfaces on the side wall thereof which are separated by a wide groove or relieved portion where the closure must be relatively rigid and self-supporting. The preferred form of closure and the container for which it is best adapted to be used will now be described.

As shown particularly in Figs. 1 and 2, the closure is cup-like in form, such as may be drawn from a pliable metal blank in a suitable die press.

It has the usual top panel, to which the reference numeral 1 is directed. Any desired identifying embossing may be formed in the top panel, but for simplicity of illustration no such embossing is shown in the drawing. The closure 1 has an upper frusto-conical skirt portion 3 joined to the top panel by a fillet 2. Below the upper skirt portion 3 there is provided a knurled mid-portion 4, connecting the upper skirt portion to a lower frusto-conical skirt portion 5. The upper and lower frusto-conical skirt portions 3 and 5 lie in concentric surfaces of revolution. The knurled mid-portion 4 has alternate roots and crests vertically aligned; and it joins the skirt portions 3 and 5 in such manner that the roots of the knurled mid-portion 4 lie substantially in the surface of revolution defined by the upper frusto-conical skirt portion 3, and the crests lie substantially in the surface of revolution defined by the lower frusto-conical skirt portion 5. The particular purpose of this construction appears hereinabove.

The container for use with which the closure 1 is particularly adapted is shown in Fig. 3. The container 10 has the usual top surface 11 provided with an upper side surface 12 on the outside lip thereof. The upper surface 12 may be described as a frusto-conical portion of the closure engaging surface of the container. In the upper surface 12, there is provided a groove 13 interrupted by lugs 14. The groove and lugs are provided for securing the closure 1 by reformation thereinto of the upper portion 3 thereof in the usual manner. Immediately below the upper surface 12 of the container 10, there is a wide, deep groove 16. An annular shoulder 15 is disposed beneath the upper surface 12 and receding therefrom, forming part of the upper wall of the groove 16. The purpose of the shoulder 15 and groove 16 are to provide an interruption or air space in the side surface of the container. Since the groove 16 and shoulder 15 form no part of the present invention, it is not necessary to further discuss their usefulness or purpose.

Immediately below the groove 16 a lower side surface 17 is provided on the side finish of the container. The lower surface 17 may also be identified as a frusto-conical portion of the closure engaging surface of the container. It may be coincident with the surface of revolution defined by the upper surface 12 and is approximately so shown in the drawing; but it may, if desired, define a frusto-conical surface of revolution concentric with that defined by the upper surface 12, parallel or not parallel thereto. The lower surface 17 is provided with a plurality of threads 18. The threads 18 are provided for additionally securing the closure by reformation thereover of the lower skirt portion 5 in the usual manner. Immediately below the lower surface 17 a suitable annular ledge may be provided, merging preferably into a bead 19 surrounding the neck of the container 10.

It will be observed that the container 10 shown in Fig. 3 is provided with an upper closure engaging surface 12 and a lower closure engaging surface 17 separated by a wide, deep groove 16. The upper surface 12 is shown provided with a securing groove 13 interrupted by lugs 14, but any other suitable closure retaining devices could be employed if desired. Likewise, the threads 18 shown on the lower surface 17 could be modified or replaced by any other suitable closure securing devices.

The closure 1 is adapted to be seated loosely on 75

the container 10 in the manner shown in Fig. 4. It will there be observed that the closure 1, before being reformed on the container 10, is disposed so that the upper and lower skirt portions 3 and 5 thereof are opposite the upper and lower surfaces 12 and 17 of the container, having the securing groove 13 and threads 18, respectively. It will be further observed that the knurled mid-portion 4 of the closure 1 is disposed opposite the wide groove 16 in the container 10. The bottom of the skirt portion 5 preferably reaches or slightly overlaps the ledge at the uppermost portion of the bead 19 so as to provide a completely protective closure for the container 10. The stepped skirt construction permits the skirt portion 5 to pass over the threads 18 prior to reformation of the closure.

The closure 1 is adapted to be reformed onto the container 10 by the method and apparatus disclosed in my application for "Closure reforming method and apparatus," Serial No. 383,936, filed concurrently with this application. A method of sealing or reforming the closure 1 on the container 10 consists of pressing the closure 1 down onto the top of the container 10 and squeezing the upper and lower skirt portions 3 and 5 in against the upper and lower closure engaging surfaces of the container, without mutilating, breaking, or distorting the closure at its mid-portion opposite the groove 16. In Fig. 5 the closure is shown as it appears when reformed on the container 10. A groove 6 will appear in the closure 1 where it is depressed into the groove 13 of the container. Interrupted portions 7 will define the positions of the corresponding lugs 14 in the container. Threads 8 will appear in the lower portion of the skirt corresponding to the threads 18 on the container 10.

From the foregoing description it will be apparent that a novel form of closure has been devised for sealing a container having separated closure engaging surfaces. A particularly strong, self-supporting closure has been provided, which has heretofore been unattainable in pliable metal such as has been described above.

Many variations may be made in the practice of this invention and it is therefore to be understood that the invention is to be considered confined only within the reasonable scope of the appended claims.

I claim:

1. A pliable metal closure having a skirt formed of upper and lower portions, and an annular band of vertical fluting, the root portions of which merge with said upper portion and the crest portions of which merge with said lower portion.

2. A pliable metal closure having initially smooth upper and lower skirt portions adapted to be reformed on a container and a pre-corrugated intermediate skirt portion.

3. A pliable metal closure having initially smooth upper and lower skirt portions adapted to be reformed on closure engaging surfaces of a container and a pre-corrugated intermediate skirt portion, the roots of which merge into said upper skirt portion and the crests of which merge into said lower skirt portion.

4. A pliable metal closure adapted to be reformed on a container having upper and lower closure engaging surfaces separated by a wide groove, and having a skirt formed of upper and lower portions joined by an undulantly formed band portion, the roots of which merge with said upper portion and the crests of which merge with

said lower portion, said band portion being adapted to strengthen and support said skirt opposite the groove on a container.

5. The combination comprising a container having upper and lower frusto-conical closure engaging surfaces separated by a wide groove, and a pliable metal closure having upper and lower frusto-conical skirt portions joined by a corrugate formed portion, said closure having said upper and lower skirt portions reformed on 10 said engaging surfaces with said corrugate formed portion opposite said groove.

6. The combination comprising a container having a frusto-conical upper closure engaging

lip provided with an annular groove interrupted by vertical ribs, a frusto-conical lower closure engaging surface provided with projecting screw threads, and a wide groove separating said lip and said surface; and a pliable metal closure having upper and lower frusto-conical skirt portions, and a corrugate formed mid-portion joining said upper skirt portion at its roots and said lower skirt portion at its crests, said upper skirt portion being reformed into said groove, said lower skirt portion being reformed on said threads, and said corrugate formed portion being disposed opposite said groove.

JOHN W. THOMAS.
